ABSTRACT OF THE DISCLOSURE

An illuminated and illuminating sign has a translucent reflector that houses the source of illumination in the centrally located dished out face portion thereof. The reflector has outwardly diverging translucent sides with a translucent and inwardly reflecting sign face positioned opposite the source and spaced outwardly of the end extremities of the diverging sides. The light source cooperates with the subject construction in that it has a wafered face plate. Each "bubble" thereon acts as an individual "light source" thereby aiding in diffusing and spreading the light rays over the entire face and through the translucent reflector. The translucent reflector may be colored, thereby producing colored light rays which are substantially the same color as the reflector in order to accentuate significant colors and objects for advertising and display purposes.

This invention is an improvement over my Patent No. 3,076,277, issued Feb. 5, 1963, entitled, "Illuminated Sign."

One object of the invention is to provide a uniquely illuminated and illuminating sign that makes maximum functional and aesthetic use of all light emanating from the source employed. This complete utilization of available light results in significant saving in lighting costs, both from the standpoint of the type and quantity of illumination sources required, as well as the watt-hour power consumption of a single source.

Another object of the invention is to provide an illuminated sign structure wherein the halo effect disclosed in my previous patent, *supra*, is enhanced and improved and wherein efficient, effective usefulness and versatility are maximized.

Another object of the invention is to provide an illuminated and illuminating sign having at least two opposed face panels, each capable of carrying advertising copy, each illuminated and illuminating in unique manner from a single light producing source and wherein at least one of the principal faces has a markedly greater display area than the adjacent area of the light source.

A further object of the invention is to provide an illuminated and illuminating sign of the character described which is uniquely adapted as to light other nearby objects and surfaces while simultaneously effectively lighting and displaying the sign.

A still further object of the invention is to provide a sign construction that produces a controlled, diffused light while simultaneously illuminating at least one face panel.

Another object of the invention is to provide for an illuminating and illuminated sign, an improved reflector structure, manufactured of translucent material such as plastic, said reflector having affixed thereto improved means for mounting a large translucent light transmitting and reflecting face panel at an extended distance therefrom, said mounting means permitting easy insertion and removal of said panel therein.

A further object of the invention is to provide an improved illuminated and illuminating sign including a re-

2

flector and a display panel wherein either or both the face panel and reflector may be constructed of translucent plastic of varied color. This feature enables sign light fluxes emanating through the various colors to be used to accentuate distinctive product colors in and around advertising displays and to illuminate ceilings or walls with pleasing light tones while simultaneously providing illuminated copy or indicia on more than one sign display face.

10 A still further object of my invention is to provide a unique method of and structure for simultaneously illuminating advertising sign display surfaces and at least a portion of a room, wherein said sign may be located, all from a single light source within the sign structure.

15 Other and further objects of the invention will appear in the course of the following description thereof.

In the drawings, which form a part of the instant specification and are to be read in conjunction therewith, embodiments of the invention are shown and, in the various 20 views, like numerals are employed to indicate like parts.

FIG. 1 is a front view of a first form of the inventive illuminated and illuminating sign showing the main display panel and a portion of the support frame therefor.

FIG. 2 is a rear elevation of the sign of FIG. 1 showing 25 the illuminated and illuminating reflector and the support frame for the front panel.

FIG. 3 is a side-elevation of the sign of FIGS. 1 and 2, the view taken from the left-hand side of FIG. 2, the sign shown chain supported, spaced outwardly from a vertical 30 wall surface.

FIG. 4 is an enlarged section taken along the line 4—4 of FIG. 2 in the direction of the arrows.

FIG. 5 is an enlarged sectional detail taken along the 35 line 5—5 of FIG. 1 in the direction of the arrows.

FIG. 6 is a side elevation of a second form of the subject sign, same shown ceiling mounted, the ceiling structure seen in section.

FIG. 7 is a top plan view of the sign of FIG. 6, looking 40 directly downwardly onto the top of the sign from the ceiling.

FIG. 8 is an enlarged sectional detail of the structure of FIG. 6 taken substantially along the line 8—8 of FIG. 6 in the direction of the arrows.

FIG. 9 is an enlarged sectional detail taken substantially along the line 9—9 of FIG. 7 in the direction of the 45 arrows.

Referring to the drawings, the reflector generally indicated by the numeral 10 is preferably substantially or entirely composed of a translucent material such as Plexiglas or other suitable plastic. All surfaces of reflector 50 10 are, to a substantial degree, smooth and polished and thereby have high reflectivity characteristics. Reflector 10 has a central dished portion 10a which forms the squared rear panel of the reflector. Perpendicular sides 10b extend outwardly from rear face 10a, forming a preferably square-shaped mounting recess of a depth appropriate to accommodate a similarly shaped light source to be later described. Angled sides 10d diverge from a lip 10c, which circumscribes perpendicular sides 10b, and terminate in a similar shaped but larger square circumscribing lip 10e. Angled sides 10d form an open-ended, frusto-conical, outwardly diverging reflector ring adjacent the face of the light source when said source is appropriately mounted. The internal surfaces of sides 10d are reflective, as noted.

The mounting recess, defined by reflector sides 10b, is particularly sized to receive a light source of panel fluorescent lamp type as seen at 11 in FIG. 4. The panel fluorescent lamp manufactured by the General Electric Company, identified by their code PF-12S lamp, works quite satisfactorily as the source of illumination. The particular named lamp, which is capable of producing approximately 4300 lumens, employs a corrugated or

wafered face plate 11a with a glass envelope 11b arranged in a serpentine fashion and formed integrally with the face plate. During normal operation, approximately 2500 lumens typically emanate through the face plate while the back of the light source gives off less than half of the source's total capacity or approximately 1800 lumens. Face plate 11a is slightly larger than the squared mounting recess and therefore circumferentially bears against and abuts the frontal exterior of lip 10c. A single clear acrylic plastic strip 12, held in place by bolted angle bracket 13, runs the length of the lower edge of face plate 11a while similar bracket 13a contacts the upper edge of face plate 11a, thereby securely locating panel lamp 11 within the mounting recess.

I have shown two different mounting embodiments for positioning the enlarged, square, translucent sign face panel 14 adjacent the reflector sides 10d, but spaced away therefrom and from the source of illumination. In regard to the shape of panel 14, it is only necessary that the panel be similar in frontal shape with that of the light source for purposes of uniform light distribution.

Referring now to FIGS. 1-5, inclusive, the sign face panel 14 is held away from reflector 10 and the entire sign is mounted in sturdy aluminum framework. As a part of this framework, structurals 15 and 16 are designed to fit and engage the inner sides of lips 10c and 10e with structural 16 bolted to lip 10e (see bolts 16a). These square-shaped structurals are then connected by diverging aluminum angles 17 which terminate in a square faced panel receiving channel generally indicated at numeral 18. As shown in FIG. 5, a set of screws 18a extend through the outer angle 18b and the inner angle 18c of channel 18, thusly locating sign panel 14 therewithin.

Ballast 19, with wiring 20 for fluorescent panel light 11, is preferably mounted so that it straddles the aluminum structurals 15 and 16. However, the ballast may be remotely located from the sign structure itself, with only wiring 20 leading to the fluorescent panel light. Alternately, and in some cases preferably for support and reflection purposes, ballast 19 will be positioned on top of, rather than under a vertically mounted reflector as shown in FIGS. 2, 3 and 4.

As seen in FIG. 3, the illuminated sign is supported by link chain 21 in a position adjacent a vertical wall surface. The link chain 21 is of the type that could hang from a conventional wall hook eye and in such instance, clear acrylic plastic stub legs (not shown) of a preselected length with rubber pads will be added to connect with structural 15, thereby supporting the illuminated sign a preselected distance from the wall. This preselected distance facilitates in the night lighting effect described later.

FIGS. 6-9 represent a different face panel mounting means and depict therein a panel face holding channel 22 and connectors 23, which are constructed of clear acrylic plastic. Channel 22 is open along one edge allowing for quick removal and replacement of face panels. The projected face panel 14 mounted in its associated holding channel 22, is held away from the translucent reflector 10 by the clear acrylic plastic connectors 23. Connectors 23 are fastened to the reflector's diverging corners by aluminum pop rivets 24, best seen in FIG. 9, and are braised to the corners of holding channel 22.

Because channel 22 and connectors 23 are made from transparent plastic rather than aluminum, it is lighter in weight and presents less light blockage and fewer shadows. As a result, this sign construction is easily portable and is sometimes set or leaned against counter or display shelves.

Another typical support for this type of illuminated sign is shown in FIG. 6 wherein the sign structure is rigidly supported from a joist or ceiling area with the accompanying ballast 19 located interiorly of the ceiling. When utilizing the rigid support mentioned above, an aluminum square frame 25 will be bolted to lip 10c at selective intervals. A pair of aluminum bar extensions 26

are welded at intervals on two sides of frame 25 and are internally threaded to connect with threaded rods 27. Rod 27 may then extend through drilled holes in ceiling 28 and threadably engage supporting plates 29 which may be nailed or otherwise connected to joist 30. The abovementioned threaded rod connection allows the distance between rear panel 10a and ceiling 28 to be selectively varied by adjustment of the externally threaded rod 27.

In my Patent 3,076,277, supra, the light source, an opaque reflector, and a translucent sign face panel were arranged in a particular fashion to produce a halo or light circle effect on the wall or backing surface surrounding the general area of the sign. By varying the position of the reflecting surface rearwardly of the sign face, the halo position and form could be varied so long as there was a separation between the reflector and the rear of the sign face panel. This separation allowed the reflected and diffused light rays bouncing off the interior of the sign face panel, for example, to pass therethrough unobstructed after their initial reflection and to finally reflect against the wall or backing surface.

The instant sign construction likewise produces the halo effect behind sign face panel 14, however the usable percentage of available light emanating from the light source is significantly increased by use of the translucent reflector 10. Direct rays from source 11 will be projected through rear panel 10a even though panel 10a is translucent, rather than transparent. Additional light emission and glow effect is had around the translucent diverging angled sides 10d. Thus direct, reflected, diffused and intercepted light rays are played against wall surfaces and other objects surrounding the rear and adjacent area of the sign.

As earlier noted, the face panel 14 and the light source should be approximately the same shape. I have found that by using a square light source such as source 11, the entire square face panel 14 is uniformly lighted with no "dead spots" located therein. Accordingly, with the instant construction, a substantially smaller light source will illuminate a much larger sign area, as well as optimizing the use of the 1800 lumens given off from the back side of the light source.

A typical example of the increased usable light is seen with reference to FIG. 3. Here the instant sign construction is shown, chain dropped a preselected distance away from the back wall of a room or store window. If, for example, the back wall is opposite the store window in the front of a building, the illuminated sign could be used both to display and convey an illuminated message on the sign face panel accompanied by the halo effect, while at the same time, transmitting sufficient direct and reflected light rays through rear face 10a of the reflector to light either the entire or a significant portion of the back wall area. Thus the illuminated sign is serving in dual capacities as both a night light and as a source of advertising illumination for the message carried on the front sign face panel.

The embodiment disclosed with reference to FIG. 6 has a similarly constructed reflector ring and light source. This mounting arrangement maintains the above-mentioned dual purpose capability of illuminating the sign panel face 14, while directly lighting the ceiling 28. In this instance, it is also contemplated that the rigid mount represented by threaded rods 27 may be replaced by link chains of the type that will allow the sign structure to be more easily raised or lowered to suit the need of projecting direct, diffused and reflected light as the circumstances may dictate. This embodiment allows illuminated signs to actually serve as the entire illuminating source for a store, office or waiting room area. The advertising indicia or copy (not shown) may still be displayed on frontal panel 14 while selectively spaced sign structures ranging from the ceiling will adequately illuminate the store, office or shop with a pleasant indirect

light. This effect is created by the direct transmission of forward light through face panel 14 as well as the reflected and diffused light rays emanating from in and around the rearwardly reflecting face panel, the translucent reflector sides and rear panel, and the various light reflecting surfaces therearound such as the ceilings and walls. This type of light, the direct, diffused and reflected rays, has a tendency to "hug" the walls and ceiling and effectively eliminates shadows around counters, desks and working areas below.

The unique sign construction greatly facilitates the advertising potential of illuminated signs. By selecting colored translucent reflectors, various prominent and identifiable trademark colors and features may be accentuated in window displays or at significant display and purchase points in retail stores. For example, the instant sign construction may be used to display advertising copy on its frontal face panel while it is chain mounted in a display window. The direct rays emanating from the light source through a color translucent reflector may highlight some significant color or object on display in the window.

When desired, the various embodiments may be mounted away from a wall and advertising indicia or copy (not shown) may be placed directly on the rear panel 10a, for an interior message, as well as the larger message on the frontal face panel 14. The sign may be revolving, stationary, mounted on a parapet or marquee or include color translucent reflectors of the type mentioned above. In this instance, transmitted, direct, diffused and reflected light rays, along with the above-mentioned halo effect results in a great deal of versatility from an advertising, illuminating and displaying standpoint.

The various sign construction mentioned above also may be utilized for its potential room illumination ability. In this instance the distance that the sign itself is positioned away from a wall surface or ceiling surface plays a significant role in the type of illumination afforded. If, for example, the above-mentioned fluorescent panel light were used as the light source in the FIG. 3 embodiment, it is estimated that the rear face 10a should be located some 5 to 6 inches away from the wall surface. This distance allows the direct, transmitted, diffused and reflected light from a single sign to sufficiently light the entire back wall of a moderately sized room. Similarly an illuminated and illuminating sign of this construction can light an area in front of a display window as well as the display window area and the room area behind it.

From the foregoing, it will be seen that this invention is one well adapted to attain all of the ends and objects hereinabove set forth, together with other advantages which are obvious and which are inherent to the structure.

It will be understood that certain features and subcombinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

Having thus described my invention, I claim:

1. An illuminated and illuminating sign comprising a translucent reflector having a centrally located dished

face portion with outwardly diverging sides extending therefrom,

5 a source of illumination positioned within said dished face portion of said reflector and operative to generate light rays outwardly of and through said dished portion,

10 said source having a wafered front panel with a rear serpentine glass envelope and operable to generate light rays both forwardly and rearwardly thereof, a translucent and inwardly reflecting sign face panel so positioned opposite said source and outwardly of the end extremities of said diverging sides that at least one-half of the direct light rays from said source of illumination must contact said panel before passing therefrom.

15 2. The invention of claim 1 wherein said sign face panel is held outwardly of the end extremities of said diverging sides in a transparent frame supported by transparent connectors.

20 3. The invention as in claim 1 wherein said translucent reflector is colored, thereby causing said illuminating light rays emanating therefrom to be substantially the color of said reflector.

25 4. The method of using a light source having a wafered face plate with a translucent envelope arranged in serpentine fashion and formed integrally with the rear of said plate, said method operable to simultaneously illuminate the front panel of a sign located in a window display area, an area in front of the window and an area behind said sign including said display area and an adjacent room area, said method comprising the steps of

30 supporting a translucent colored reflector with said source of illumination therein a preselected distance from the ceiling of said display area, projecting at least one-half of the direct light rays emanating from said source onto the rear face of a translucent and rearwardly reflecting sign face panel that is spaced away from said reflector, directing substantially all the remaining direct light rays from the serpentine glass envelope through said reflector and into contact with said window display area and said adjacent room area behind said sign, and projecting frontally emanating direct, diffused and reflected light rays from said sign construction and said display area through said window and into contact with an area in front of said window said method thereby simultaneously illuminating said window display area, adjacent room area, an outside area in front of said window and the front panel of said sign with light rays substantially the color of said translucent reflector.
